UNITED STATES PATENT OFFICE.

ALBERT E. DURLAND, OF SEATTLE, WASHINGTON.

BOX-ASSEMBLING APPARATUS.

1,315,915.

Specification of Letters Patent.

Patented Sept. 9, 1919.

Application filed December 27, 1915, Serial No. 68,744. Renewed March 10, 1919. Serial No. 281,795.

To all whom it may concern:

Be it known that I, ALBERT E. DURLAND, a citizen of the United States, residing at Seattle, in the county of King and State of Washington, have invented certain new and useful Improvements in Box-Assembling Apparatus, of which the following is a specification.

This invention relates to improvements in box-assembling apparatus.

The principal object of the invention is the provision of simple and conveniently operated devices for holding the box-ends in proper spaced alinement so that the box-sides may be handily nailed in place. Foot-operated devices are provided for turning the box-parts to successively present the sides and bottom of the box uppermost whereby the operator may most readily secure the parts together.

Another object of the invention is the provision of devices for presenting a plurality of box-ends in position to be easily grasped by the operator to economize his time and to make for the maximum efficiency of the machine.

Still further objects of the invention will be evident in the following specification.

In the accompanying drawings, Figure 1 is a view in front elevation of a box-assembling machine embodying my invention. Fig. 2 is a view substantially in side elevation of the same, although taken on section line 2—2 of Fig. 1. Fig. 3 is a partial plan view of said machine illustrating the box-end clamping mechanism. Fig. 4 is a detail side view of said box-end clamping mechanism. Fig. 5 is an end view of Fig. 4. Fig. 6 is a detail view in front elevation of the box-turning devices and adjacent parts. Fig. 7 is a view on section line 7—7 of Fig. 6. Fig. 8 is a view in longitudinal section of one of the supporting knees for the box-ends. Fig. 9 is a view on section line 9—9 of Fig. 45 8. Fig. 10 is a perspective view of a modified form of an element of the machine.

Referring to said views, wherein similar reference characters denote similar parts in the several views, the reference numeral 10 indicates the front upright posts and 11 the rear posts of a substantially rectangular frame. Said posts 10 are connected by horizontal frame-bars 12 and 13, and posts 11 by suitable frame members, while transverse frame-bars such as 14 and 15 and various

brace-members are so disposed where needed to provide a rigid framework of relatively light and rigid character.

Vertical standards 16, 16 are provided at each side of the frame supported at their lower ends upon the frame bars 14 and are connected at their upper ends to the respective rear post 11 by horizontal brace-bar 17. Said standards are formed with guide-slots 18 and 19 in which longitudinal rod 20 and superposed arbors 21 of a vertically reciprocating carriage are guided. Said carriage is further provided with vertical bars 22, 22 and 23, 23 at each side connecting said rod 20 with the arbors 21, said arbors being slidably as well as revolubly connected with said bars. Bars 22 and 23 are maintained in relatively fixed position by inclined brace 25 and the bars 22 are formed with a rearwardly extending semi-circular bowed portion 22¹ (see Fig. 2) which provides a bearing at each end of the machine for a cam-shaft 26 and a parallel alinement rod 27.

A semi-circularly bowed support 28 is provided for the inner end of each said arbor having an open side facing to the front and slidably connected intermediate its ends to the rod 27 and at its lower end to the rod 20.

A clamping plate 30 is rigidly mounted upon the inner extremity of each of said arbors 21. Said carriage is further provided with clamping members 31 adapted to coact with the plates 30 to secure a box-end in operative position therebetween. Said members are secured to bowed supports 32 of similar configuration to supports 28 and have their lower end slidably mounted upon the rod 20 while their rearward intermediate portion is similarly associated with the shaft 27, and adapted to be adjustably and pivotally secured thereto by set-screw 32¹. Said supports 32 are further formed with a rearward apertured extension 33 through which the rod 26 extends, as clearly shown in Fig. 4. Upon each said extension 33 upon the side opposite to which the respective clamping members 31 are positioned, is a cam 35 with which is engaged an integral finger 36 of a set-collar 37 fixedly mounted on the rod 26.

Said extension and cam are pressed in yielding engagement with said collar by a coil-spring 38 surrounding rod 26 and confined by set-collar 40. The effect of these just-described devices is such that the spring 110

38 normally presses the clamping member 31 toward the respective plate 30 to clamp a box-end therebetween, the support 32 having a slight rocking movement upon the rod 5 27. When the rod 26 is rocked in the proper rotary direction through the crank-lever 41 manipulated by the operator through the pull-rod 42, the finger 36 will react upon the inclined face of the cam 35 and force the 10 tension 33 against the pressure of the spring 38 to separate the clamping-members 30 and 31.

Said carriage as a whole is arranged to be reciprocated in vertical directions, the rod 15 20 and the arbors 21 being guided in slots 18 and 19, as aforesaid. Such movement of the carriage is accomplished by the operator pressing with his foot upon the hinged treadle 43 which is connected intermediate 20 its length through rings 45 with the levers 46 which are fulcrumed at 47 and connected with the vertical bars 23 through links 48.

A counterweight 50 serves to equalize the weight of the carriage, being connected 25 thereto by flexible connections 51.

Fixedly secured upon the respective arbors 21 is a sleeve 52 to which is rigidly secured or integrally formed a star-wheel 53 having four equally spaced radiating arms 55. Said 30 arms are adapted to engage, in turn, an adjustable stop 56 upon the upward travel of the carriage, and cause the arbors 21 to make one-fourth of a revolution at each upward stroke of the carriage. The inner end 35 57 of said sleeve 52 is made square in cross-section, as shown in Fig. 7, while one side of said guide-slot 19 which engages with said squared portion 57, is formed of a strip 58 hinged at one end 59 while its other end is 40 retained in yielding engagement against the respective flat surfaces of the end 57 by a spring 60. Thus the pressure exerted by the strip 58 upon the sleeve tends to maintain the star-wheel in suitable relation to 45 the stop 56 to effect the movements required.

As the box-ends are seldom of square configuration, it is desirable to provide limit stops for the carriage at different elevations at each alternate reciprocation of the carriage and to take the impact and weight 50 of the carriage so that the same is not borne by the box-ends. To this end, slidably adjustable stops 61 and 61¹ are mounted upon said sleeve 52 extending in diametri-

55 cally opposite directions and arranged to hit upon a projecting bracket 62 secured to the frame at each alternate quarter-turn of the arbors 21 to limit the downward movement of the carriage. At each intermediate 60 downward reciprocation of the carriage an adjustable screw or other stop 63 is provided on the side of the frame to be engaged by the rod 20 on the downward stroke.

65 Supported on horizontal longitudinal frame-members are horizontal transversely

arranged knees 65, 65¹ of which the middle one 65¹ is fixedly secured intermediate the length of the frame while the outer knees 65 are adjustable longitudinally of the frame through bolt and thumb-nut connections, indicated at 66.

70 Referring to Figs. 8 and 9 wherein said knees are illustrated in detail, it will be seen that in the form now considered, the horizontal knee 65 is surmounted by a metal casting 68 having a chamber 68¹ formed with a slot 70 in its upper wall. A metal block 67 bifurcated at each end is adjustably secured along the length of said chamber by a bolt 71 received within the forward bifurcation 80 of the block. Within the rear bifurcation, a dog 72 is pivotally secured at one end at 73 while its opposite end 75 is normally pressed upwardly to protrude through said slot 70 by a spring 76, said end 75 forming a 85 stop to guide the positioning of the box-ends quickly upon the knees before the clamps 30 and 31 are engaged therewith.

77 indicates an inclined or other shelf whereon are piled the boards within easy 90 reach of the operator's hand for nailing upon the box-ends to form the side walls of the boxes. The box-ends may be similarly positioned upon shelf 77 so as to be readily grasped by the operator, but I prefer to provide a separate rack and operating mechanism whereby such box-ends may be mechanically presented to the operator's hand. 95

100 Referring particularly to Figs. 1 and 2, the reference numeral 78 indicates an inclined rack adapted to retain the box-ends 79 in vertical position, whereby the latter are caused to move forwardly toward the front open end of said rack as the foremost box-ends are removed. Abutment blocks 105 80 are provided at each side of said open end of the rack against which the front box-end engages, said blocks 80 being adjustable in the side-walls 81 of the rack by means of thumb-nuts 82.

110 83 indicates a plunger adapted to engage the lower end of the box-ends, which is operated in vertical directions by the upward movements of the main carriage, by means of a lever 84 fulcrumed at 85 connected by 115 a link 86 to an end of a lever 87 pivoted at 88 whose opposite end is engaged by the rod 27 when the carriage is actuated in upward directions.

120 In its upward movements the plunger 83 engages the foremost two or three of the box-ends 79 and elevates them above the adjacent box-ends, as indicated at 79¹, where they may be readily grasped by the operator and placed between the clamping plates 125 when a new box is to be formed.

130 The elevated box-ends 79¹ are retained in their elevated position by friction between the adjacent box-ends and the blocks 80. The plunger 83 is reciprocated upwardly at 130

each upward stroke of the carriage but does not engage any of the box-ends until those already elevated are removed and the remaining box-ends have moved downwardly 5 into the path of the plunger.

The plunger is arranged to engage either two or three of the box ends, or any number desired, by adjusting the blocks 80 through said thumb nuts 82. Similar feeding devices 10 for the box sides may be provided either at the side of the operator or superimposed upon the machine, as upon the shelf 77.

It will be noted that intermediate clamping plates 90 are provided which are utilized 15 when the box is to be made with a transverse partition therein, as is customarily provided in some forms of fruit boxes.

In this case the knee 65¹ is built rigid upon the frame and the supports 28¹ and 32¹ 20 may be fixed relative to said knee, excepting that the support 32¹ is adapted to be opened and closed through the partial rotation of the cam rod 26, as is the case with the clamping plate supports heretofore described.

25 In operation, the operator first grasps two of the box-ends and positions them upon the knees 65 and alines them against the adjustable stop 72 which is yieldingly thrust up above the plane of said knees. In the case of a partitioned box, it will be understood that three of the box-ends are utilized, 30 one being positioned upon the knee 65¹, as indicated in dotted lines in Fig. 1.

The operator then grasps the pull-rod 42 35 to actuate the cam-rod 26 to close the clamping members 31 and secure said box-ends against the plates 30. He then takes one or more of the box sides resting upon the shelf 77 and nails them upon the top, uniting the 40 rectangular sides of the box-ends. After the said box sides are secured, the operator pushes with his foot downwardly upon the treadle 43, which actuates the carriage upwardly. In the upward movement of the 45 carriage the respective arm 55 of the star-wheel 53 engages the adjustable stop 56 and causes the arbors 21 to turn one-fourth of a revolution, turning the box-ends with the nailed side an equal amount whereby, when 50 the carriage returns on its downward stroke, the box-ends will again rest on the knees 65 in position to have the box sides nailed upon its second side.

After the second side is nailed securely, 55 the carriage is again elevated to cause the partially completed box to present one of its unfinished sides at the top, whereupon the third side is nailed thereon, and the box is complete with the exception of nailing on 60 the cover, which is done after the box is filled with its contents.

As the box-ends are usually rectangular in shape but longer in one dimension than the other, the stops 61 and 61¹ are regulated

to support the weight of the carriage upon 65 the brackets 62, when the longer dimensions of the box are arranged in vertical directions. In this position the box-ends are brought up against the stop 72.

When the box is turned to present the 70 longer dimensions of the box-ends in horizontal directions, the carriage will descend somewhat lower and the stops 63 are adjusted to interfere with the rods 20, while the stops 61 and 61¹ are rotated with the 75 arbors 21 to horizontal directions.

The box-ends, as they again rest upon the knee 65, extend over the stop 72 whereupon the latter is yieldingly pressed down within the slot 70 and does not interfere with the 80 support of the box-ends upon the knees. Said knees 65 may be slidably adjusted longitudinally of the machine to accommodate the same to various lengths of boxes. The corresponding parts, such as the clamping 85 members 30 and 31, with their supports, are also adjusted to conform to the various sizes of boxes assembled.

Where relatively narrow boxes are to be formed, such as are used for peach or 90 cherry-boxes, the clamping members 30 are desirably formed of rectangular configuration, as shown in Fig. 10, of lesser dimensions than the box-ends so that the box-ends will extend outwardly beyond the clamping 95 members and rest upon the knees without interference.

Having described my invention, what I claim, is—

1. In a box assembling machine, a frame, 100 a carriage vertically slidable in said frame, a pair of arbors mounted for rotation in said carriage, a clamping plate upon the inner end of each of said arbors, clamping members carried by said carriage and adapted to coöperate with said plates to secure box ends in position, means to actuate said clamping member to secure or release a box end between the same and said plates, means to reciprocate said carriage in vertical directions, a stop carried by said frame, and devices associated with said arbors and engaging said stop at each upward movement of said carriage to rotatively actuate 110 said arbors.

2. In a box assembling machine, a frame, 120 a carriage vertically slidable in said frame, means to reciprocate said carriage, a plurality of knees arranged transversely of the frame, a pair of arbors mounted for rotation in said carriage, a clamping plate upon the inner end of each of said arbors, clamping members carried by said carriage and adapted to coöperate with said plates to secure box ends in position, devices for actuating said clamping members relative to said clamping plates whereby a box end may be secured therebetween, a stop carried 125

by said frame, and devices actuated by said stop for turning said arbors a partial rotation upon each reciprocation of the carriage.

- 5 3. In a box assembling machine, a frame, a carriage vertically movable in said frame, means to reciprocate said carriage, a plurality of knees arranged transversely of the frame and adjustable longitudinally of the 10 frame, a pair of arbors mounted for rotation in said carriage and adjustable longitudinally thereof, a clamping plate upon the inner end of each of said arbors, clamping members adapted to coöperate with said 15 plates to secure box ends in position, means to adjust said clamping members longitudinally of the frame, devices for actuating said clamping members relative to said clamping plates whereby a box end may be secured 20 therebetween, and devices for turning said arbors a partial rotation upon each reciprocation of the carriage.

4. In a box assembling machine, a rigid frame, a vertically slidable carriage supported in said frame, means to actuate said carriage in vertical directions, clamping jaws carried by said carriage and adapted to hold box ends in position, a stop carried by said frame, and means actuated by said 25 stop whereby said clamping jaws are given a partial rotation at each vertical movement of the carriage.

5. In a box assembling machine, a frame, a carriage vertically slidable in said frame, 30 said carriage having a plurality of parallel rods extending longitudinally thereof, a pair of rotatable axially alined arbors each provided with a clamping plate at its inner extremity, a pair of supports slidably 35 mounted on said rods between said arbors and each provided with a clamping member adapted to coact with one of said plates to secure a box end therebetween, and means to actuate said supports and clamping members 40 relative to said plates.

6. In a box assembling machine, a frame, a carriage vertically slidable in said frame,

means to actuate the carriage in vertical directions, box end clamping devices associated with said carriage including axially alined arbors rotatively mounted in the carriage, and trip devices including stops carried by said frame arranged to rotate said arbors at each vertical movement of the carriage.

7. In a box-assembling machine, a frame, a carriage vertically movable in said frame, and means to actuate the carriage in vertical directions, box-clamping devices associated with said carriage including axially alined arbors rotatively mounted in the carriage, trip-devices arranged to actuate said arbor in rotary directions at each vertical movement of the carriage, and adjustable stops arranged to support the weight of the carriage when in its lowermost position.

8. In a box-assembling machine, a frame, a carriage vertically movable in said frame, and means to actuate the carriage in vertical directions, box-clamping devices associated with said carriage including axially alined arbors rotatively mounted in the carriage, trip-devices arranged to actuate said arbor in rotary directions at each vertical movement of the carriage, and adjustable stops arranged to support the carriage at different elevations at each alternate movement of the carriage.

9. In a box-assembling machine, a rigid frame, a vertically movable carriage supported in said frame, means to actuate said carriage in vertical directions, means to secure the box-ends in operative position, and apparatus associated with said machine and actuated by the movement of said carriage whereby a plurality of box-ends are presented in position to be grasped by the operator.

Signed at Seattle, Wash., this 13th day of December 1915.

ALBERT E. DURLAND.
